LIFTING MAGNET

Howard E. Hodgson, Wauwatosa, Wis., assignor
to Cutler-Hammer, Inc., Milwaukee, Wis., a
corporation of Delaware

Application October 22, 1937, Serial No. 170,334

6 Claims. (Cl. 175—367)

This invention relates to improvements in electromagnets, and while not limited thereto is particularly applicable to lifting magnets.

Lifting magnets usually comprise a magnet frame having concentrically arranged inner and outer pole projections, a coil unit mounted in the space between the pole projections and an annular coil shield secured between the pole projections to form with the magnet frame a complete enclosure for the coil unit. In the patent to Howard E. Hodgson et al., No. 2,095,499, dated October 12, 1937, there is disclosed a lifting magnet of this type having a cast coil shield which is secured to the inner and outer pole projections by continuous welded connections, the coil shield being of special form to facilitate welding thereof. Welded lifting magnets of the type disclosed in the aforementioned application have numerous advantages, but in some instances it has been found that cast coil shields are defective and do not provide for proper sealing of the coil unit within the magnet frame.

The present invention has among its objects to provide a lifting magnet of the welded type which overcomes the aforementioned objection.

Another object is to provide a lifting magnet having coil shielding means which is inexpensive and also of sturdy construction and which is particularly adapted for use in connection with lifting magnets of large diameter.

Various other objects and advantages of the invention will hereinafter appear.

The accompanying drawing illustrates an embodiment of the invention which will now be described, it being understood that the embodiment illustrated is susceptible of modification without departing from the spirit and scope of the appended claims.

In the drawing,

40 Figure 1 is a vertical sectional view of a lifting magnet embodying the invention;

Fig. 2 is a fragmentary bottom view of the lifting magnet shown in Fig. 1 with the inner and outer pole shoes of the magnet removed, and

45 Figs. 3 and 4 are enlarged fragmentary sectional views of certain of the parts shown in Fig. 1.

Referring to Fig. 1, the same illustrates a lifting magnet provided with a magnet frame 1 having a hollow cylindrical center pole projection 2 and an annular outer pole projection 3 on the under side thereof. A coil unit 4 is mounted in the annular space between the pole projections 2 and 3, and said unit comprises a core

member 5 bored to fit over pole projection 2, an annular plate 6 mounted upon the upper end of said core member and a plurality of windings 7 mounted upon said core member, each of said windings being formed of strap material and being insulated in the usual manner.

5 Coil unit 4 is sealed within the space between pole projections 2 and 3 by an annular sealing disk 8 formed of sheet metal and having its inner edge secured to pole projection 2 by a continuous welded connection 9, and its outer edge secured to pole projection 3 by a continuous welded connection 10. Coil unit 4 and sealing disk 8 are protected by a shield 11 of annular form located between the pole projections 2 and 3 and held in place by inner and outer pole shoes 12 and 13 fixed to said pole projections.

More specifically, the upper face of sealing disk 8 engages the lower face of coil unit 4 and the inner edge of said disk is formed to provide a downwardly extending flange 14 while the outer edge thereof is formed to provide a downwardly extending flange 15. The inner flange 14 is of such diameter as to fit tightly around the inner pole projection 2 and the lower end of said pole projection is of reduced diameter to provide a shoulder 16 which is flush with the lower edge of said flange. The lower end of outer pole projection 3 is counterbored to provide a shoulder 17 which forms an abutment for the outer marginal portion of sealing disk 8, and the outer flange 15 of said sealing disk is of such diameter as to fit tightly within said counterbore. Also the lower end of outer pole projection 3 is counterbored to provide a shoulder 18 which is flush with the lower edge of flange 15. The inner welded connection 9 extends between the lower edge of flange 14 and shoulder 16 on inner pole projection 2, while the outer welded connection 10 extends between the lower edge of flange 15 and shoulder 18 on outer pole projection 3. The flanges 14 and 15 render the marginal portions of the sealing disk relatively flexible to minimize strains on the welded connections 9 and 10, and welding of the sealing disk 8 to pole projections 2 and 3 insures proper sealing of coil unit 4 within the magnet frame 1.

Shield 11 comprises a casting of annular form having inner and outer portions 20 and 21 of increased thickness which are finished on opposite sides. Shield 11 is located between the flanges 14 and 15 on sealing disk 8 and the inner and outer edges thereof are spaced from said flanges. However, the inner marginal por-

tion of shield 11 extends below core member 5, while the outer marginal portion thereof extends below shoulder 17 on outer pole projection 3. The lower face of coil shield 11 is provided with 5 radially arranged projections 22 which are V-shaped in cross section to eliminate cooling strains in the casting.

As hereinbefore stated, shield 11 is secured to the magnet frame by inner and outer pole shoes 10 12 and 13. The inner pole shoe 12 is of circular form and is secured to inner pole projection 2 by bolts 23 passing through openings in said pole projection and having their heads countersunk in the lower face of said pole shoe. Inner pole shoe 12 is of such diameter as to engage the inner 15 marginal portion 20 of shield 11 and the upper face of said pole shoe is provided with an annular flange 24 which is turned to fit within the opening in coil shield 8. Flange 24 is shouldered as 20 shown at 25 to clear flange 14 of sealing disk 8 and the welded connection 9, and the same is bored to fit the lower end of inner pole projection 2. The inner pole shoe 12 thus serves to hold 25 shield 11 in centered relation with respect to the magnet frame, and the arrangement is such that upon tightening of bolts 23 the inner marginal portion 20 of shield 11 and sealing disk 8 are clamped between said inner pole shoe and the lower end of core member 5. The outer pole shoe 30 13 is secured to an outwardly extending flange 26 on the lower end of outer pole projection 3 by bolts 27 having their heads countersunk in the lower face of said outer pole shoe. Said outer pole shoe is provided with an upwardly extending peripheral flange 28 which is bored to receive the flange 26 on outer pole 3 and the inner marginal portion 35 thereof is counterbored to receive the outer edge of shield 11 and to provide a shoulder for engaging the under face of the marginal portion 20 of shield 11. Upon tightening of bolts 27 shield 11 and sealing disk 8 are clamped between the outer pole shoe 13 and the shoulder 17 on outer pole projection 3. The channels on the upper face of shield 11 formed by the radial projections 40 22 are filled with a material such as concrete to provide rapid conduction of heat from the coil unit to shield 11. Also the upper side of magnet frame 1 is provided with an opening 38 for receiving the terminals of coil unit 4, one of 45 said terminals being illustrated at 31, and said terminals are each connected to an insulated terminal element 32. The terminal elements are located within a pocket 33 formed in the upper face of magnet frame 1 and opening 38 is closed 50 by a removable cover plate 34 while pocket 33 is closed by a removable cover plate 35. The upper face of the magnet frame is also provided with the usual suspension lugs, one of which is illustrated at 36.

60 What I claim as new and desire to secure by Letters Patent is:

1. In a lifting magnet, in combination, a magnet frame having concentrically arranged inner and outer pole projections, an annular coil unit 65 mounted in the space between said pole projections, an annular sealing disk formed of thin sheet metal and mounted in the space between said pole projections to form with said magnet frame a complete enclosure for said coil unit, continuous welded connections between said magnet frame and the inner and outer edges of said disk, and rigid supporting means engaging the under side of said sealing disk and supporting said disk substantially throughout to prevent flexing 70 of any part thereof, said supporting means in- 75

cluding a rigid shield of annular form secured to said inner and outer pole projections.

2. In a lifting magnet, in combination, a magnet frame having concentrically arranged inner and outer pole projections on the under side thereof, an annular coil unit mounted in the space between said pole projections, an annular sealing disk formed of thin sheet metal and mounted in the space between said pole projections to form with said magnet frame a complete enclosure for 10 said coil unit, said sealing disk having a downwardly projecting flange formed on its outer edge tightly fitting within said outer pole projection and a downwardly projecting flange formed on its inner edge tightly fitting around said inner pole projection, continuous welded connections between the lower edges of said flanges and said magnet frame and rigid supporting means engaging the under side of said disk and supporting said disk substantially throughout to prevent flexing 15 of any part thereof, said supporting means including a rigid shield of annular form secured to said inner and outer pole projections.

3. In a lifting magnet, in combination, a magnet frame having concentrically arranged inner and outer pole projections, an annular coil unit mounted in the space between said pole projections, an annular sealing disk formed of thin sheet metal and mounted in the space between said pole projections to form with said magnet frame a complete enclosure for said coil unit, continuous welded connections between said magnet frame and the inner and outer edges of said disk, a rigid shield of annular form secured to said inner and outer pole projections, said shield having its upper face recessed to provide inner and outer flange projections which engage the under side of said sealing disk adjacent said welded connections and a filler of compacted material held within the recess in the upper face of said shield and engaging the under side of said sealing disk to prevent flexing of the latter.

4. In a lifting magnet, in combination, a magnet frame having concentrically arranged inner and outer pole projections on the under side thereof, an annular coil unit mounted in the space between said pole projections and having a core member bored to receive said inner pole projection, an annular sealing disk formed of thin sheet metal and mounted in the space between said pole projections to form with said magnet frame a complete enclosure for said coil unit, said outer pole projection being shouldered to provide an annular abutment for the outer marginal portion of said sealing disk, continuous welded connections between the inner and outer edges of said sealing disk and said inner and outer pole projections, and rigid supporting means engaging the under side of said disk and supporting said disk substantially throughout to prevent flexing 50 of any part thereof, said supporting means including a rigid shield of annular form secured to said inner and outer pole projections and engaging said sealing disk to clamp the same against the annular abutment on said outer pole projection and the lower end of said core member.

5. In a lifting magnet, in combination, a magnet frame having concentrically arranged inner and outer pole projections on the under side thereof, an annular coil unit mounted in the space between said pole projections, an annular sealing disk formed of thin sheet metal and mounted in the space between said pole projections to form with said magnet frame a complete enclosure for said coil unit, said sealing disk hav- 70 75 75

ing downwardly extending circular flanges formed on the inner and outer edges thereof, continuous welded connections between the lower ends of said flanges and the inner and outer pole projections on said magnet frame, a rigid shield of annular form engaging the under side of said sealing disk, said disk having its upper face recessed to provide inner and outer flanges which engage said sealing disk adjacent said welded connections, pole shoes secured to said inner and outer pole projections and engaging said shield to secure the same to said magnet frame and to clamp the same against the lower face of said sealing disk, and a filler of compacted material held within the recess in the upper face of said shield and engaging the under side of said sealing disk to prevent flexure of said sealing disk and to also provide for rapid conduction of heat from said coil unit to said shield.

20 6. In a lifting magnet, in combination, a magnet frame having concentrically arranged inner

and outer pole projections, an annular coil unit mounted in the space between said pole projections, an annular sealing disk formed of thin sheet metal and mounted in the space between said pole projections to form with said magnet frame a complete enclosure for said coil unit, continuous welded connections between said magnet frame and the inner and outer edges of said disk, a rigid shield of annular form engaging the under side of said sealing disk, said shield having 5 radially arranged projections on the under side thereof which are V-shaped in cross section to provide radial channels in the upper face of said shield and a filler of compacted material between the lower face of said sealing disk and the upper 10 face of said shield for preventing flexure of any part of said sealing disk and for also effecting rapid conduction of heat from said coil unit to said shield.
